COMBINATION WIND AND RAIN SHIELD ATTACHMENT FOR AUTOMOTIVE VE- HICLES

Joseph E. Baker, Newark, Ohio

Application May 29, 1950, Serial No. 10,255

Term of patent 3½ years

(Cl. D14—6)

To all whom it may concern:

Be it known that I, Joseph E. Baker, a citizen of the United States of America, residing at Newark, in the county of Licking and State of Ohio, have invented a new, original, and ornamental Design for a Combination Wind and Rain Shield Attachment for Automotive Vehicles, of which the following is a specification, reference being had to the accompanying drawing, forming a part thereof.

Fig. 1 is a perspective view of a combination wind and rain shield attachment for automotive vehicles, showing the present design;

Fig. 2 is a top plan view thereof;

Fig. 3 is an end elevational view; and

Fig. 4 is a transverse vertical sectional view taken along the line 4—4 of Fig. 2.

I claim:

The ornamental design for a combination wind and rain shield attachment for automotive vehicles, substantially as shown.

JOSEPH E. BAKER.
